Primary Examiner—Jeffrey Asch

(57) **CLAIM**

I claim the ornamental design for the base transceiver station for mobile network, as shown.

DESCRIPTION

FIG. 1 is a perspective front view of the base transceiver station for a mobile network;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective front view thereof; and,

FIG. 9 is a perspective rear view thereof.
